MAH JONG COIN HOLDER TRAY

Sally F. Raphael, 128 N. Craig St., Pittsburgh, Pa.

Filed Mar. 12, 1963, Ser. No. 73,929

Term of patent 14 years

(Cl. D34—13)

FIG. 1

FIG. 2

FIG. 4

FIG. 3

FIG. 5

FIG. 1 is a top plan view of a mah jong coin holder tray showing my new design;

FIG. 2 is a side elevational view thereof from the line 2—2 of FIG. 1;

FIG. 3 is a transverse sectional view thereof from the line 3—3 of FIG. 1;

FIG. 4 is a side elevational view taken along the line 4—4 of FIG. 1; and

FIG. 5 is a side elevational view taken along the line 5—5 of FIG. 1.

The other side views and the bottom view are plain.

I claim:

The ornamental design for a mah jong coin holder tray, substantially as shown and described.
